UNITED STATES PATENT OFFICE.

JOHN WILSON BROWN, JR., OF PHILADELPHIA, PENNSYLVANIA.

POWER MEAT-CHOPPER.

SPECIFICATION forming part of Letters Patent No. 562,279, dated June 16, 1896.

Application filed December 6, 1895. Serial No. 571,272. (No model.)

To all whom it may concern:

Be it known that I, JOHN WILSON BROWN, Jr., a citizen of the United States, residing in Philadelphia, Pennsylvania, have invented 5 certain Improvements in Power Meat-Choppers, of which the following is a specification.

One object of my invention is to construct a power meat-chopper which can be driven by belting and the parts of which can be readily 10 detached for cleansing or repairs; and a further object of my invention is to provide for the easy running of the chopper.

In the accompanying drawings, Figure 1 is a longitudinal view of my improved meat-chopper. Fig. 2 is a plan view. Fig. 3 is a 15 section on the line 3 3, Fig. 1. Fig. 4 is an enlarged sectional view showing the ball-bearing.

A is the base-frame of the meat-chopper, having 20 two standards $a a'$, on which are mounted the bearings a^2 for the shaft B. On this shaft are a fast pulley b and a loose pulley b' . Secured to the front of the frame A by bolts d is the meat-chopper casing D, having a hopper D'. In the standard a of the frame A is a recess a^3 , forming with the casing D a receptacle for lubricating material. 25

On the end of the driving-shaft B is a head B', having a cavity b^2 , in which the rear end 30 e of the feed-screw E rests. This end and cavity are so formed that the feed-screw will turn with the shaft, but is loose in the head, so that it will accommodate itself to the casing. Back of the flange of the head is a hardened metal plate b^3 , resting against balls f, confined between the two plates $f' f^2$, which are recessed to receive them, and these two plates are secured together by rivets, so that 35 they form a ball-bearing washer, the balls being so arranged between the plates that they cannot become detached should the washer be removed from the machine. The balls rest against a hardened bearing-disk F, abutting against the face of the standard a , so that 40 pressure caused by the perforated plate bearing against the knife will not interfere to any great extent with the free rotation of the shaft and as the lower portion of the disk carrying the balls is below the level of the lubricating 45 material in the receptacle, the lubrication of this part of the machine is insured. The shaft B can be readily removed by simply withdrawing the feed-screw E, detaching the caps 50

of the bearings a^2 and the lid a^4 , after which the shaft can be taken away for repairs or adjustment. 55

Screwed onto the casing D is a ring D^2 , confining a perforated plate D^3 in position against the knife E'. The ring D^2 has an annular recess d' , formed by the annular flange and the 60 lip d^2 . This lip rests directly against the plate, and the recess is sufficient to receive the end of the casing, so that by this arrangement the plate can be adjusted to a greater extent than heretofore, to take up the wear. 65 The screw E has a spindle e' , which extends through the knife and rests in a bearing in the perforated plate, as clearly shown.

G is the belt-shifter rod, having the frame g, through which the belt passes. This rod is 70 adapted to guideways d^3 on the hopper D' and is connected at h to a shifting-lever H, which is pivoted to the hopper at h' , so that on moving this lever H the belt can be shifted either onto the fast or loose pulleys. 75

I claim as my invention—

1. The combination in a power meat-chopper, of the frame having two standards, a casing secured to the face of one of said standards, a shaft adapted to bearings on the 80 standards, a head on the shaft, an antifriction thrust-bearing between the head and the standard, a feed-screw adapted to the casing and connected to the shaft, with a cutter and a perforated plate and means for adjusting 85 the plate in respect to the cutter, substantially as described.

2. The combination in a power meat-chopper, of the frame A, standards $a a'$, boxes on said standards, a casing D secured to the front 90 of the standard a and forming with the frame a receptacle for lubricating material, a shaft B having a recessed head, a feed-screw having a shank adapted to a recess in the head of the shaft, and an antifriction - bearing mounted 95 between the head and the standard and arranged so as to be continuously lubricated, substantially as described.

In testimony whereof I have signed my name to this specification in the presence of 100 two subscribing witnesses.

JOHN WILSON BROWN, JR.
